United States Patent Office

Des. 188,102
Patented June 7, 1960

188,102

MOLDED COMPOSITION CONNECTOR

Henry W. Yarick, Jr., 1251 Cleveland Road,
Glendale, Calif.

Filed July 1, 1958, Ser. No. 51,616

Term of patent 14 years

(Cl. D26—1)

Figure 1 is an elevation view of a molded composition connector showing my new design.

Figure 2 is a fragmentary view of the connector of Figure 1.

The dominant features of my design are shown in full lines.

I claim:

The ornamental design for a molded composition connector, as shown and described.
